UNITED STATES PATENT OFFICE.

WILLIAM A. ALRICH, OF CHATHAM, VIRGINIA.

SEWING-MACHINE ATTACHMENT.

SPECIFICATION forming part of Letters Patent No. 249,733, dated November 22, 1881.

Application filed August 20, 1881. (No model.)

To all whom it may concern:

Be it known that I, WILLIAM A. ALRICH, of Chatham, in the county of Pittsylvania and State of Virginia, have invented certain new and useful Improvements in Sewing-Machine Attachments; and I do hereby declare that the following is a full, clear, and exact description of the invention, which will enable others skilled in the art to which it appertains to make and use the same, reference being had to the accompanying drawings, which form a part of this specification.

This invention relates to a ripping attachment for sewing-machines, the construction and operation of which will be hereinafter more fully described, and particularly pointed out in the claim.

My invention consists of a narrow sharp blade capable of being secured in the needle-bar of any ordinary sewing machine, and operated by the mechanism of such machine, so as to cut or rip seams previously made in an easy, convenient, and effectual manner.

In the drawings hereto annexed, Figure 1 represents my invention as attached to a sewing-machine, of which only the head, needle-bar, and bed-plate are shown; and Fig. 2 is a perspective view of my improved cutter detached.

Similar letters of reference indicate corresponding parts in both figures.

A in the drawings refers to the needle-bar, and B to the bed-plate, of any ordinary sewing-machine.

D is the sharp narrow knife-blade which constitutes my invention, and which is so constructed as to be capable of being secured in the needle-opening of the needle-bar. To effect this end the said knife is provided with a suitably-constructed shank, C.

In operation, the presser-foot is to be removed from the machine, and the blade D substituted in lieu of the needle. Sewed material may then be fed as in sewing, and ripped by the knife or cutter.

This invention is applicable to different sewing-machines, and especially in shuttle-machines. It will effect a considerable saving of time in ripping goods when necessary. Another use to which my invention may be advantageously applied is that of cutting out goods for dress-patterns, which may in this manner be done more rapidly and far less laboriously than with the scissors.

I am aware that knives or cutters capable of being attached to the needle-bar of sewing-machines adjoining the needle are not new, such being shown, for example, in the patents to Dwyer, January 2, 1877, and Allen, May 27, 1873, and such I do not claim. In these cases the needle, if not removed, will interfere with the operation of the cutter, and a separate opening for the latter must be cut in the bed-plate, which is very undesirable, as, besides weakening the bed-plate, it will accumulate dust and lint, and be apt to catch and arrest the progress of goods being sewed.

By my invention the cutter may be attached to any sewing-machine without making the slightest change in the construction thereof, and the cutters may be furnished at a trifling cost.

Having thus described my invention, I claim and desire to secure by Letters Patent of the United States—

The combination, with the needle-bar of a sewing-machine, of a knife or cutter, D, having shank C, adapted to the needle-opening of said needle-bar, by which it may be secured in said opening, so as to work in the needle-opening of the bed-plate, as herein described, for the purpose shown and specified.

In testimony that I claim the foregoing as my own I have hereto affixed my signature in presence of two witnesses.

WILLIAM A. ALRICH.
